UNITED STATES PATENT OFFICE.

JOHN B. MURRAY, OF ELLWOOD CITY, PENNSYLVANIA.

PIANO-ACTION.

1,034,489.

Specification of Letters Patent.

Patented Aug. 6, 1912.

Application filed November 22, 1911. Serial No. 661,694.

To all whom it may concern:

Be it known that I, JOHN B. MURRAY, a citizen of the United States, residing at Ellwood City, in the county of Lawrence and State of Pennsylvania, have invented certain new and useful Improvements in Piano-Actions, of which the following is a specification, reference being had to the accompanying drawings.

10 My invention relates to new and useful improvements in piano actions and more particularly to the means for securing a bridle strap to the hammer and my object is to provide a simple and efficient means for securing the bridle strap to the butt of the hammer, which means will obviate the many difficulties now experienced in the present means employed.

15 A further object of the invention resides in providing a spring member removably secured to the hammer butt of a piano action, a portion of which is adapted to engage the bridle strap and secure the same in position on the butt.

20 25 A still further object resides in providing an improvement for securing the opposite end of the bridle strap to the rod of the jack lever of the action and another object is to provide a device which, while simple and durable in construction, is inexpensive to manufacture and very efficient in operation.

25 30 With these and other objects in view, my invention consists in the novel features of construction, combination and arrangement of parts as will be hereinafter more particularly pointed out in the specification and claims.

35 40 In the accompanying drawing forming a part of this application Figure 1 is a side elevation of a piano action, as much of the same being shown as is deemed necessary to illustrate the proper application of the improvement thereon; Fig. 2 is a section as seen on line 2—2 of Fig. 1; Fig. 3 is a vertical section as seen on line 3—3 of Fig. 1, and Fig. 4 is a section through that portion of the rod and the jack lever to which one end of the bridle strap is secured.

45 50 In carrying out my invention, I shall refer to the drawing in which similar reference characters designate corresponding parts throughout the several views and in which 1 indicates a hammer, the butt 2

thereof being provided with the usual counter-check 3 and 4 indicates the jack lever having the usual rod 5 mounted thereon.

55 60 The usual method of securing a bridle strap in position between these elements is by securing one end thereof to the rod 5 while the opposite end of the same is glued or otherwise applied to the hammer butt by some adherent matter and as this method has proved to be a poor one, the same embodying a great many difficulties in the operation thereof, I provide my improvement which consists in first providing a pin or the like 6 on the hammer butt 2 immediately below the counter check 3, to which pin is engaged, by merely inserting the same 65 thereover, the one end of a bridle strap 7. The side faces of the hammer butt 2 are provided with vertical channels or slots 8, the lower ends of which communicate with a channel 9 which extends transversely 70 through said hammer butt and a wire spring member 10, which is looped a number of times in its length to give the required tension, has the arms thereof disposed in said slots 8 and the free ends of 75 said arms bent to extend within the transverse channel 9.

80 85 In order to securely retain two arms in their respective slots 8 and the bent free ends thereof in the channel 9, a ring or eye member 11 is encircled about the pair of arms in order to move thereon so as to rest against the hammer butt 2 and securely retain said arms in position and the opposite or looped end of the spring member 10 is bent so as to 90 be disposed against that portion of the butt 2 in which the pin 6 is disposed. This end of the spring member is the effective end thereof and is looped in this portion, as shown at 12, to provide an eye or the like 95 through which the pin 6 is adapted to extend, when said spring is in its effective position, and it will be seen that after the one end of the bridle strap 7 has been properly positioned on the pin 6 said spring may 100 be allowed to effectively engage said strap and detachably retain the same on the pin against the hammer butt. The opposite end of the bridle strap 7 is engaged with the upper end of the rod 5 which is threaded, as 105 shown at 13, said threaded portion being engaged with the nuts 14 and 15, between which is disposed said bridle strap. Thus,

it will be seen that after the strap has been positioned thereon between said nuts, the latter may be turned on the threaded portion 13 so as to be brought toward one another thereby securing the bridle strap to the rod 5.

In practice, it will be seen that the spring member 10 may first be secured to the hammer butt by disposing the arms thereof in the slots 8 and the free ends of the same in the channel 9 of said hammer butt, whereupon the ring 11 may be moved on said arms so as to cause the same to fit tightly within their respective slots. The one end of the bridle strap 7 is then engaged with the pin 6 and the free and effective end of the spring member 10 allowed to engage said bridle strap to detachably retain the same against the hammer butt 2. The bridle strap may then be guided through the head portion of the counter check and engaged with the threaded portion of the rod 5 and locked in position thereon by the nuts 14 and 15, as described above.

From this construction it will be appreciated that the numerous obstacles and difficulties which are experienced in the use of the means now employed for securing the bridle straps on the hammer butt, will be obviated and that, should it for any reason, whatsoever, become necessary to remove the bridle strap or the like, the same may be very quickly and readily accomplished.

Furthermore, it will be seen that the means in general is one of extremely simple and durable construction, it is inexpensive to

manufacture and is one which is very efficient and useful in operation.

What I claim is:

1. In a piano action, the combination with a hammer butt and a bridle strap; of a pin secured to said hammer butt with which said bridle strap is engaged, and a spring member detachably retaining said bridle strap in engagement with said pin against said hammer butt. 40

2. In a piano action, the combination with a hammer butt and a bridle strap; of a pin secured to said hammer butt with which one end of said bridle strap is engaged, and a spring member removably secured to said hammer butt and having a portion thereof engaged with said bridle strap to detachably secure the same on said pin and against the hammer butt. 50

3. In a device of the class described, the combination with a hammer butt and a bridle strap; of a pin secured to said hammer butt with which one end of said bridle strap is engaged, a spring member, and means to removably secure the same to said hammer butt, said spring having a portion thereof bent to encircle the pin and contact with said hammer butt, whereby the bridle strap will be detachably secured to the latter. 60

In testimony whereof I hereunto affix my signature in the presence of two witnesses.

JOHN B. MURRAY.
